UNITED STATES PATENT OFFICE.

THOMAS FORSYTH, OF NEW HAVEN, CONNECTICUT, ASSIGNOR TO THE FORSYTH DYEING CO., OF NEW HAVEN, CONNECTICUT, A CORPORATION OF CONNECTICUT.

COMMERCIAL PROCESS FOR RECLAIMING THE DYE CONTENT OF WASTE LIQUORS.

1,242,676.

Specification of Letters Patent.

Patented Oct. 9, 1917.

Application filed December 1, 1916. Serial No. 134,272.

To all whom it may concern:

Be it known that I, THOMAS FORSYTH, a citizen of the United States, and resident of the city of New Haven, in the county of New Haven and State of Connecticut, have invented certain new and useful Improvements in Commercial Processes for Reclaiming the Dye Content of Waste Liquors, of which the following is a specification.

This invention relates to a new process of reclaiming commercially the dye-content of wash waters, dye baths, waste liquors and the like.

Heretofore the dye-content from waste liquors produced in commercial dyeing with sulfur colors has been lost, with the result that the net cost of dyeing with such colors has included the cost of the entire dye-content, that unappropriated and lost as well as that actually taken up by the goods.

The object of this invention is to recover for re-use the unappropriated or unused portion of this dye-content from the waste waters.

A further object of the invention is to provide a method whereby this process may be carried on continuously if desired.

The invention further consists in the provision of a process wherein the precipitated dye stuff may be collected and deposited on filtering screens located over a precipitation tank to drain back thereinto so that any of the dye-content which may pass through the filtering screens will be again collected in the precipitation tank and again deposited on the screens thereby reducing the loss in the final discharge waters to the minimum.

By the use of my commercial process two essential advantages are obtained; first, that portion of the dye stuff which is not taken up by the goods is reclaimed to be used again, thus materially reducing the cost of dyeing over the old method, which is that of permitting this unused dye stuff to pass with the wash waters into the nearby streams and rivers; second, by removing this dye stuff from the waste water before permitting it to escape, is of great public benefit as it prevents these highly colored

and malodorous liquors produced in dyeing with sulfur colors, from polluting the streams and other waters and killing of the animal life therein and the rendering unsanitary and objectionable the neighboring territory.

With these ends in view, my invention consists in a process of recovering the dye-content of the wash waters, waste liquids, dye baths, and the like, produced in dyeing with sulfur colors, the said process consisting in treating such waste or wash waters, and the like with a substance that neutralizes the solvent effect of the alkaline sulfid initially used for rendering the sulfur dye stuff soluble in water, whereby the sulfur dye stuff is again rendered insoluble after which it is reclaimed from the water as insoluble sulfur dye stuff.

With these and other objects in view, the invention, consists of certain novel features as will be more fully described, and particularly pointed out in the appended claims.

In the accompanying drawing:

Figure 1— is a diagrammatic view of an apparatus capable of carrying out the different steps of the invention.

Fig. 2— is a side elevation of the precipitation tank showing the over-flow and the well from which the precipitate is collected and removed to be deposited on the filter screens.

Fig. 3— is a perspective view showing one form of filter screens.

Since the object of my method is to neutralize the solvent effect of the alkaline sulfid initially used for rendering the sulfur dye stuff soluble, I may use an acid substance or a metallic salt for this purpose, or if desired I may blow air under pressure into the liquor to obtain this neutralization effect.

In practising my invention by the use of an acid substance, a sufficient amount thereof is introduced into the wash waters, to throw the dye-content thereof from solution, after which the now insoluble dye-content is recovered by filtration, precipitation, or in some other suitable way. The dye stuff

thus recovered is substantially identical in chemical character with the original dye stuff. On account of its cheapness and efficiency, I prefer to employ ordinary sulfuric acid which, however, I may replace by hydrochloric or some other acid, or in place of the acid I may employ an acid compound such, for instance, as bi-sulfate of sodium, or bi-sulfate of potassium or some other acid salt. In some cases as stated above I may inject air into the wash waters which when well mixed with the solution also serves to neutralize the solvent effect of the solvent employed.

15 In carrying out my improved process the waste or wash waters are drawn from the machine or other receptacle 10 in which the work was subjected to the dyeing liquor, by opening the valve 11 permitting this waste 20 to pass through the conduit 12 on its way to the precipitation tank presently described. The liquor may be caused to pass through this conduit either by the action of a pump or by gravity.

25 Preferably after the liquor has entered the conduit, I introduce therein a sufficient amount of metallic salt or other neutralizing agent from the container 13 to thoroughly neutralize the solvent, which neutralizing 30 agent enters the conduit through the inlet 14. In other instances I admit air from the pressure tank 24 through the pipe 25 into these waste or wash waters, which air upon being thoroughly mixed with these waters 35 oxidizes the sulfid used in dissolving the dye stuff, which oxidization neutralizes the solvent and releases the dye stuff from solution.

The mixture of wash waters containing 40 its neutralizing agent now passes on through the conduit and is deposited into the mixing tank 15 which is provided with impediments such as a bed of jagged rocks or other suitable means which serves to agitate and mix 45 the neutralizing agent as the liquid is forced or passes over and around the same.

After passing through this agitating receptacle the liquor is deposited into the precipitation tank 23, which is provided with 50 flaring drip boards 16 over which the filter screens 17 are located.

This precipitation tank is also preferably provided with an inclined bottom portion 18 and a well 19 in which the precipitate collects to be drawn therefrom, either intermittently or continuously by a pump 20 and distributed by means of the head 21 into the different filter screens 17 above the tank. Instead of a pump for this purpose the precipitate may be collected by any suitable 60 means and subsequently deposited on the filter screens.

These filter screens as illustrated in Fig. 3 are preferably in rows of looped screen cloth

hung on beams above the tank and over its 65 flaring drip boards, whereby the drip from these screens with such dye-content as may work therethrough falls back into the tank where it will eventually again find its way into the well 19 to be again removed, deposited and collected on the screen bed. It is obvious that the screen cloth which is well known in the art, is porous and that the pores thereof assist in drawing the moisture from the sludge by capillary attraction. 75 Thus the sludge is filtered by gravity and is subjected to evaporation by atmospheric action.

It will be noted that the waste waters from this precipitation tank after the dye-content has settled, is permitted to over-flow the upper edge of the tank as at 21 into the waste conduit 22 which waste water is now entirely cleaned of its dye-content and may be discharged into streams or rivers without 85 detrimental effect.

My improved process, in addition to furnishing a commercial means whereby a valuable dye-content of wash waters, waste liquors and dye baths produced in dyeing 90 with sulphur colors may be reclaimed and saved at very small cost, is also of great public benefit in overcoming to a large degree the pollution of streams and other waters into which the waste with its highly colored 95 and malodorous liquors has been emptied.

I claim:

1. An improved process of reclaiming the dye contents of waste dye liquors comprising drawing off the waste liquors from the 100 dyeing receptacle, incorporating a neutralizing agent into the liquor as it flows from said receptacle, then agitating the liquor while flowing to thoroughly incorporate said neutralizing agent, and finally filtering said 105 liquor.

2. An improved process of reclaiming the dye contents of waste dye liquors comprising drawing off the waste liquors from the dyeing receptacle, incorporating a neutralizing 110 agent into the liquor as it flows from said receptacle, impeding the flow of the liquor at a plurality of irregularly disposed points to agitate the liquor while flowing, whereby thorough incorporation of said neutralizing 115 agent is effected, and finally filtering said liquor.

3. An improved process of reclaiming the dye contents of waste dye liquors consisting in incorporating a neutralizing agent into the liquor, effecting a preliminary separation of the precipitated sludge from the liquor, and finally filtering the sludge by gravity and subjecting the same to evaporation by atmospheric action while being 120 125 filtered.

4. An improved process of reclaiming the dye contents of waste dye liquors comprising

drawing off the waste liquors from the dyeing receptacle, incorporating a neutralizing agent into said liquor, then agitating the liquor to thoroughly incorporate said neutralizing agent, and finally separating the precipitated sludge from the liquor.

In testimony whereof I affix my signature in presence of two witnesses.

THOMAS FORSYTH.
